Primary Examiner—Susan J. Lucas*Assistant Examiner*—Jennifer Rivard*Attorney, Agent, or Firm*—Harter, Secrest & Emery LLP; Stephen B. Salai[57] **CLAIM**

The ornamental design for a device tag for display of electrical devices, as shown and described.

DESCRIPTION

FIG. 1 is a perspective view of the tag.

FIG. 2 is a front plan view of the tag of FIG. 1.

FIG. 3 is a side elevational view of the tag of FIG. 1.

FIG. 4 is a rear plan view of the tag of FIG. 1; and, FIG. 5 is a perspective view showing the tag of FIG. 1 in cooperative orientation with respect to an electrical display device.

The broken lines are shown for illustrative purposes only and form no part of the claimed design.
